HANDBAG

Ernest Konelsky, Paris, France

Application October 17, 1936, Serial No. 106,079

12 Claims. (CL. 150—42)

This invention relates to devices such as containers, handbags and the like, and to devices such as closures of the slide fastener type.

One object of the invention is to provide a device of the character described having improved means for opening and closing an opening of normally substantial area without requiring any distortion of the main part of the body in which the opening is provided.

Another object is to provide a device of the character described comprising a strip closure element which, in the open position of the fastening, assumes a folded or compacted relation such that it will not obstruct the opening or otherwise interfere with the free use of the device.

Another object of the invention is to furnish a device of the nature set forth including parallel slide fasteners for an opening and a single actuator for the slides thereof adapted to also act as a closure for an end of the opening.

Heretofore handbags have been provided with a single slide fastener which necessitated considerable spreading and distortion of the bag to afford free access to the contents. If the bag was bulged by the contents, difficulty was frequently encountered in closing the bag, because of sticking of the slide fastener.

It is therefore an object of the invention to overcome the above mentioned difficulties, and to provide a handbag which is normally not distorted whether open or closed.

A further object of the invention is to furnish a device of the character mentioned having few and simple parts, and which is inexpensive to manufacture and assemble, durable, reliable, accurate, easy and efficient in operation.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in side elevation showing a device embodying the invention, in closed position.

Fig. 2 is a top plan view thereof.

Fig. 3 is a view in side elevation thereof in open position.

Fig. 4 is a top plan view of the same.

Fig. 5 is an enlarged fragmentary sectional view taken on the line 5—5 of Fig. 4.

Fig. 6 is a plan view of a plate actuator.

Fig. 7 is a sectional view taken on the line 7—7 of Fig. 6.

Fig. 8 is a top plan view showing a modification of the invention.

Fig. 9 is a sectional view of a modified attaching means for the slide elements.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device such as a container, handbag or other article adapted to have an opening that is to be releasably closed. The bag of the device 10 may have side walls 11, arranged so as to be amply spaced apart at the top marginal opening 12. The latter is of substantial width, being provided preferably by longitudinal parallel slits or margins 13, and an end slit or margin 14 to thus define a strip closure element 15, which is connected at its other end to the bag wall, as at 16. The closure element 15 is interfitted in the bag walls so as to lie substantially in the plane thereof in a neat and compact manner.

Releasably interengaging the longitudinal parallel edges of the closure element 15 and the opening 12 are slide means of any suitable type, for example, slide fasteners comprising rows of hooks 17 connected to the different edges, and actuated by a suitable operating means such as 40 the sliders 18. The otherwise free end 19 of the strip closure 15 is, however, free of the slide fasteners.

For actuating the slide fasteners as a unit, an actuator 20 is provided. The same may comprise a holder portion such as a rigid plate 21 arranged to closely overlie the closure 15. The sliders 18 may be connected to this plate by rigid means, such as a wire 22 soldered or spot welded thereto and having downwardly bent portions 23 adapted to engage the sliders 18 as by passing through the upright flanges thereof as at 24. If desired, the wire may be soldered to said flanges, so that relative movability between the sliders is limited or substantially entirely eliminated. Thus the 55

sliders may be readily moved in true alinement with the rows of interengaging hooks 17. Moreover, any upward pull on the plate 21 is taken up by both slide fasteners, so that distortion is avoided and easy operation assured.

If desired, the plate 21 may be encased between a pair of leather pieces or plates such as 24, 25, and an ornamental button or finger piece 26 may be suitably secured thereon.

10 The elongation of the actuator 20 is sufficient so that the ends thereof may act as finger pieces adapted to be grasped to cause opening and closing movement of the slide fasteners. Aid in this action may be afforded by the end tabs 27, 28 connected to the bag at the opposite ends of the opening 12.

To prevent the closure strip 15 from dangling down or interfering with the access to the bag in the open position thereof, the end 19 of the closure is connected at 29 to the actuator 20. Since the closure is highly flexible it can fold at any point, from full closed to full open position, shown in Fig. 3, in which the closure strip assumes a highly compacted form. In the closed 25 position of the bag, the actuator 20 overlaps the end 14 of the opening 12 to a sufficient degree to properly close the same.

It will now be seen that the device 10 can be opened up by a single motion to afford an opening 30 the full width of the bag. The bag contents are then easily viewed and are accessible without distorting the bag. The opening action is easily effected by grasping the left end of the actuator 20 in one hand and pulling it toward the tab 27, 35 which is grasped in the other hand. A reverse action in conjunction with the tab 28 is used to close the bag. During the closing, the slide fasteners are not subjected to any lateral pull due to any possible bulging of the side walls 11 by 40 the contents of the bag, because the slide fasteners embrace a substantial area. Hence sticking and catching is avoided. The sliders 18 work true with their respective rows of hooks or fastening elements, and finally the actuator 20 closes 45 the end 14 of the bag opening.

When the bag is open the strip closure is in folded compacted form. The closely overlying position of the actuator 20 in slidable relation to the closure 15 also makes for compactness and ease of operation.

50 The strip element when in such open position functions very conveniently as a handle for the bag. The operator can securely grasp the loop in one hand while removing contents from the bag with the other hand. Since the walls of the bag are flexible, such holding of the bag precludes any collapse of the bag by holding pressure.

In Fig. 8 is shown a device 30 embodying a modification of the invention. This device is exactly the same as the device 10 except that the strip closure 15 is detached at both ends from the bag, a means 20 being provided at each end of the strip cover for suitable actuation of the releasable fastening means from either end, for the added convenience of the operator. Moreover, by opening the slide fasteners at both ends of the cover member, an article too large to be completely housed in the bag, may be received or secured therein, with the end portions projecting from opposite ends of the bag opening.

70 In Fig. 9 is shown a sectional view of a modified means of interconnecting elements 18, including a plate 35 corresponding to plate 21, and having openings at 36 formed to each provide opposed downward projecting tongues 37 between which

an element 18 is insertable so as to be gripped thereby upon pressing the plate 21 downward on the elements 18 to flatten the tongues 37 as shown at the left, causing the tongues to lock into the channel spaces of the elements 18. 5

I claim:

1. A generally rectangular ladies' handbag including an edge wall having parallel slits, a cross slit at one end thereof to constitute the material intermediate of the parallel slits, a strip-like closure connected at the other end to the container, releasable interconnecting means between the edges of the respective parallel slits, sliders for operating the individual interconnecting means, a rigid finger piece actuator member, means rigidly connecting the member to the sliders for moving the latter in true alinement with the interconnecting means, said member extending slidably transversely over the strip-like closure and having means for its manipulation intermediate of 15 the sliders for actuating the latter as a unit.

2. A narrow elongated ladies' handbag including an edge wall having an elongated opening and a strip portion consisting of flexible material connected at one end to said wall to close said opening, with the opposite end of the strip portion free of the wall, the longitudinal edges of said opening and strip portion being free and having releasable interengaging means extending therewith, individual slide elements for operating the 30 interengaging means, means consisting of rigid material interconnecting the slide elements for actuation thereof as a unit, said means closely overlying the strip portion in the engaged and released positions of the interengaging means 35 and serving to rigidly space the slider elements at a fixed distance from each other in opening and closing movements of said elements.

3. A ladies' handbag including an edge wall having an elongated opening and a strip portion 40 connected at one end to said wall to close said opening, with the opposite end of the strip portion free of the wall, the longitudinal edges of said opening and strip portion being free and having releasable interengaging means extending 45 therewith, individual slide elements for operating the interengaging means, means interconnecting the slide elements for actuation thereof as a unit, said means closely overlying the strip portion in the engaged and released positions of 50 the interengaging means, said interconnecting means having an extension for overlying the free end of the strip portion in the closed position thereof.

4. A container including a wall having an 55 opening, and a flap like closure element for said opening adapted to lie in the plane of said wall in interfitted relation with said opening, the closure having its opposite longitudinal edges parallel and in relative proximity to each other, 60 the closure having a free end, slide fasteners for the parallel edges, operating means therefor, the slide fasteners terminating at the free end of the closure, and means interconnecting the operating means to actuate the same as a unit, said 65 interconnecting means comprising a relatively flat plate like element adapted to closely overlap the free end of the closure and the adjoining portion of said wall.

5. A container including a wall having an open- 70 ing, and a flap like closure element for said opening adapted to lie in the plane of said wall in interfitted relation with said opening, the closure having its opposite longitudinal edges parallel and in relative proximity to each other and hav- 75

ing a free end, slide fasteners for the parallel edges, operating means for the slide fasteners, the slide fasteners terminating at the free end of the closure, and means interconnecting the 5 operating means to actuate the same as a unit, said interconnecting means comprising a relatively flat plate like element adapted to closely overlap the free end of the closure and the adjoining portion of said wall, and the free end of 10 said closure being connected to said plate like element so as to fold back upon itself upon moving the operating means toward open position.

6. A device including a wall having an elongated opening and a strip portion connected at one end to said wall to close the said opening, with the opposite end of the strip portion free of the wall, the longitudinal edges of said opening and strip portion being free and having re- 15 leasable interengaging means extending therealong, individual slide elements for operating said interengaging means, means interconnecting the slide elements for actuation thereof as a unit, and means interengaging the free end of 20 the strip portion with the interconnecting means, as and for the purpose set forth.

7. A narrow elongated ladies' handbag having an opening along an edge thereof, a strip element for closing said opening, said strip element 30 having parallel longitudinal edges, slide fasteners for connecting said edges to the adjoining edges of said opening, and relatively rigid means engaged with the slide fasteners for actuating both of them as a unit.

35 8. A narrow elongated ladies' handbag having an opening along an edge thereof, a strip element for closing said opening, said strip element having parallel longitudinal edges, slide fasteners for connecting said edges to the adjoining 40 edges of said opening, and means engaged with the slide fasteners for actuating both of them as a unit, said means including a perforated plate overlying the strip element and connected to the sliders of the slide fastener means at the 45 perforations of the plate.

9. A ladies' handbag having an opening along an edge thereof, a strip element for closing said opening, said strip element having parallel longitudinal edges, slide fasteners for connecting 50 said edges to the adjoining edges of said open-

ing, and means engaged with the slide fasteners for actuating both of them as a unit, said means including an actuator plate connected to the sliders of the slide fastener means, said plate having an extension for overlapping an adjacent 5 end of the opening in the closed position of the handbag, said strip element terminating within said adjacent end of said opening.

10. A handbag having an elongated opening, a flexible strip like cover for said opening, one 10 end of the cover being connected to the bag in relatively fixed relation thereto, and holding means for the cover slidably connecting the other end of the cover to the bag to permit the cover to be moved and folded into open position, said 15 strip like cover in the open position affording a looped handle for the bag.

11. A handbag provided with an elongated opening, a strip cover for said opening, releasable fastening means extending along and inter- 20 connecting the free longitudinal edges of said opening and said strip cover, elements at each end of each fastening means for controlling the same, means for interconnecting a pair of the elements at each end of the strip cover for actuation of the pair of elements as a unit, whereby the strip cover can be released to full open position from either end thereof and the strip cover can be partially opened at both ends to provide 25 a centrally closed bag opening open at its ends 30 for holding a projecting article in the bag.

12. A device including a ladies' handbag consisting of a receptacle having generally parallel side walls, and narrow bottom and end walls, said receptacle having a top opening extending from 35 end to end thereof and being substantially the full width of the handbag for easy access thereto, a strip of pliable material forming a closure for said opening, and slide fasteners for interconnecting the longitudinal edges of the strip 40 closure with the edges of said opening, including slide means for the slide fasteners, and means interconnecting the slide means for operation as a unit, including a relatively rigid plate in relatively rigid relation to the interconnecting means 45 and forming a supplemental closure to overlie and close an end of said opening in the closed position of the strip closure.

ERNEST KONELSKY. 50
